FOLDABLE TRAY AND CONTAINER ATTACHMENT FOR AN INVALID CHAIR

Lester H. Bennett, 11482 Foster Road,
Rossmoor, Calif. 90720

Filed Oct. 26, 1971, Ser. No. 192,702

Term of patent 14 years

Int. Cl. D3—99

U.S. Cl. D83—1 R

FIG.1

FIG.2

FIG.3

FIG.4

FIG.5

FIG.6

FIG.7

FIG. 1 is a perspective view of a foldable tray and container attachment for an invalid chair showing my new design;

FIG. 2 is a perspective view thereof in open condition;

FIG. 3 is a front elevational view;

FIG. 4 is a rear elevational view;

FIG. 5 is a top plan view;

FIG. 6 is a right side elevational view; and

FIG. 7 is a bottom plan view.

I claim:

The ornamental design for a foldable tray and container attachment for an invalid chair, substantially as shown and described.
